UNITED STATES PATENT OFFICE.

NATHAN W. HENDRYX, OF NEW HAVEN, CONNECTICUT, ASSIGNOR TO THE ANDREW B. HENDRYX COMPANY, OF NEW HAVEN, CONNECTICUT, A CORPORATION OF CONNECTICUT.

DESIGN FOR A BIRD CAGE.

Application filed November 13, 1926. Serial No. 19,723. Term of patent 14 years.

To all whom it may concern:

Be it known that I, NATHAN W. HENDRYX, a citizen of the United States, residing in New Haven, New Haven County, Connecticut, have invented a new, original, and ornamental Design for a Bird Cage, of which the following is a specification, when taken in connection with the accompanying drawings, of which—

Fig. 1 is a front elevational view of a bird cage, embodying my new design;

Fig. 2 is a side elevational view of the cage.

I claim:

The ornamental design for a bird cage substantially as shown.

NATHAN W. HENDRYX.
